(74) Attorney, Agent, or Firm—Banner & Witcoff, Ltd.

(57) **CLAIM**

The ornamental design for a cooking pan cover, as shown and described.

DESCRIPTION

FIG. 1 is a perspective view of a cooking pan cover showing my new design;

FIG. 2 is a front elevational view thereof, the rear elevational view thereof sharing the same appearance;

FIG. 3 is a right side elevational view thereof, the left side elevational view thereof sharing the same appearance;

FIG. 4 is a top plan view thereof; and,

FIG. 5 is bottom plan view thereof.

The broken line showing of the side handles of the cooking pan cover is for illustrative purposes only and forms no part of the claimed design.
